UNITED STATES PATENT OFFICE.

HANS PEARSON, OF ALCESTER, SOUTH DAKOTA.

MAIL-CARRYING DEVICE.

No. 838,747.

Specification of Letters Patent.

Patented Dec. 18, 1906.

Application filed April 9, 1906. Serial No. 310,647.

To all whom it may concern:

Be it known that I, HANS PEARSON, a citizen of the United States, residing at Alcester, in the county of Union and State of South Dakota, have invented certain new and useful Improvements in Mail-Carrying Devices; and I do declare the following to be a full, clear, and exact description of the invention, such as will enable others skilled in the art to 10 which it appertains to make and use the same, reference being had to the accompanying drawings, and to the figures of reference marked thereon, which form a part of this specification.

15 My invention relates to rural mail-delivering devices; and the object is to provide an inexpensive device by which farmers and others who get their mail deposited in a box at the side of the country road, which is often 20 hundreds or even thousands of feet away from the residence, may have the mail brought home to the house without walking to the roadside for it, a trip which is especially objectionable in the winter season. This 25 and other objects I attain by the novel construction and arrangements of parts illustrated in the accompanying drawings, and which consist of a certain arrangement of posts and lines or wires supported therein 30 and serving to transfer the mail-box between the roadside and the house or residence.

In the drawings, Figure 1 is a side elevation of such transferring-line with the mail-box at the roadside. Fig. 2 is a cross-section 35 on the line *a* in Fig. 1 with the mail-box just passing the post. Fig. 3 is a top view of the end of the line at the roadside. Fig. 4 is a modification. Fig. 5 is a top view of the guides 17 shown in several of the other 40 views. Fig. 6 is a side view of the mail-box as suspended from the transferring-cable by two hangers. Fig. 7 is Fig. 6 with only one hanger. Figs. 8, 9, 10 are modifications of the upper portion of Fig. 2.

45 In the following description it may appear as if some parts and features in the drawings are overlooked; but that is because they have been described and claimed in another application, Serial No. 310,646, filed simultaneously with this one. In said other application I use a wire or track for the support of the mail-box and an endless cable to move the box with, while in the present construction I dispense with such track and let the 50 endless cable support the box. This and other improvements will be fully understood

from the drawings, which will now be referred to by reference-numerals.

1 designates the ground; 2, the farmer's house or a stationary object near the house. 60 3 is a post near the roadside 4, where the rural mail-delivering wagon passes along and deposits the mail into the mail-box 5 when the latter is in the position shown in Fig. 1. Between the terminal points 2 and 3 are 65 fixed in the ground posts 15 in such numbers as the distance or length of the line may require.

The mail-box 5 is suspended by a hanger or arm 6, of which there may be one, as in Fig. 7, 70 or two, as in Fig. 6, from the lower strand 7 of an endless cable, wire, or chain stretched over the pulleys 8 and 9, of which the latter has a crank 10 fixed on its shaft 11, journaled in a bracket 12, fixed upon the object 2. 75 The other pulley 8 revolves on a pin 13, inserted in a frame 14, projecting from the post 3 out over the road 4, so that the mail-wagon may drive partly in under the frame, and thus reach the mail-box very conveniently. Said 80 frame 14 may consist of a single arm from a single post, as in Fig. 3, or it may be U-shaped and secured to two posts, as in Fig. 4, where the line is long and may have a tendency to twist or turn a single post. A frame similar 85 to 14 may be used at the other end of the line for delivering the mail-box through a suitable opening into the house.

Upon each of the intermediate posts 15 is secured a bracket 16, which may be modified 90 in form, as shown by 16^a, 16^b, and 16^c in Figs. 8, 9, and 10, respectively.

In Fig. 2 the hanger 6 of the mail-box is curved in and downward between the guides 17 (best shown in Fig. 5) and by a 95 double-tapered tube 18, fixed to the lower strand 7 of the cable, whose upper strand is supported in an aperture 19 in the upper part of the bracket, preferably upon a sheave 20. The lower strand is guided and supported by 100 the grooved sheaves 21 22, revolving on the studs 23 and 23^a, which have the guides 17 fixed to their upper ends. From the bracket-arm 23^a projects a horizontal stud 24, carrying a roller 25, which helps to support 105 the cable 7. The arm 23 is pivoted at 26 and is by a spring 27 at all times pressed with its sheave 22 toward the cable. Its motion is, however, controlled by two fingers 28 on an arm 29, secured at 30 upon the bracket. To 110 prevent the tube 18 from breaking on the sheaves 21 22 when the box is swinging in the

wind, the guides 17 are to guide the arm 16 while it passes between the sheaves. This may also be accomplished by having the guides fixed, as 17^a, on a special arm 31, extending from the post below the box, and a guide 32, fixed underneath the box, so that it passes between the guides. In the modifications Figs. 8 and 10 is shown that such lower arm may be formed integral with the main bracket.

Upon the house or other fixed object 2 is mounted a signal-bell 33, on which strikes a hammer 34, operated by a spring 34^a and a cord or wire 35, having its other end fixed to a lever 36, pivoted upon the frame 14, so that the mail-carrier may ring the bell, and thus inform the owner of the box that mail was deposited. Said signal-wire may be guided in staples 37, driven into the posts, or preferably in holes in the bracket, as indicated at 38 in Fig. 2 or 38^a in Fig. 8.

In the modification Fig. 8 the sheaves 21 22 revolve in the vertical plane, and the spring-pressed arm 23^b has a guarding-hook 40 to keep the cable-strand 7^a on the sheave, and the hanger 6^a is less curved than 6 in Fig. 2.

In Fig. 9 the hanger 6^b is suspended directly downward from the cable 7, and the sheave 22 revolves on a rectangular member 41, sliding in a groove 42 in the bracket 16^b, in which groove it is retained by the head 43 of a bolt screwed into the bracket through a slot 39 in the member, so that the spring 27^a 35 has a chance to force the member, with the sheave 22, toward the sheave 21, whereby the cable is always retained in the meeting grooves of said sheaves, the spring yielding only enough to let the hanger of the mail-box 40 pass between them. In this form the guides 17 and arms 31 32 in Fig. 8 are used; but for obvious reason it is not necessary to show them in both views.

In Fig. 10 the sheaves 21^a and 22^a are placed in axial or central position to each other. Their grooves are modified, as shown, and one sheave is fixed on a short shaft 44, the other on a longer shaft 45, both revolving in the bracket; but the shaft 45 may also slide 50 against the resistance of the spring 46 sufficiently to allow the hanger 6^b of the box to pass between the two sheaves when either one of the tapered ends of the tube 18 (best shown in Fig. 7) forces the sheaves apart and 55 let the hanger pass between them, whereupon the sheaves close again and guide the cable only. The pulley 9 is grooved, so as to get a good hold on the cable, which is operated in either direction by turning the crank 60 10. If said crank is about six inches long and the pulley is about twenty-four inches in diameter, the mail-box will come and go about as fast as a good bicycle-rider.

In Fig. 1, 47 is a coil-spring encircling a bolt 65 48, sliding in the frame 14 and having an

elongated head or arm 49 meeting the hanger 18 close up under the cable. When such meeting takes place, the operator feels at the crank 10 that the spring 47 yields and rebounds, and he knows thereby that the box 70 is at the end of the line whether he can see it or not.

It will be seen that the various modifications are all for the same principle—viz., to carry the letter-box suspended from and 75 fixed to an endless cable operated by a pulley and crank, and to guide and support such cable by grooved pulleys, of which one is spring-pressed toward the other and is only forced away by the necessary enlargement on 80 the cable where the hanger of the box is connected to it, and to guide the hanger or box so that it will not break on the sheaves.

Having thus described my invention, what I claim, and desire to secure by Letters Patent, is—

1. A mail-carrying device comprising a line of posts, a grooved pulley at each end of the line, an endless cable extending over the pulleys, a mail-box secured by a hanger or 90 hangers to the cable; a crank operatively connected with one of the pulleys, brackets fixed on the posts intermediate the ends of the line, and spring-closed grooved sheaves mounted on the brackets for guiding and 95 supporting the cable.

2. A mail-carrying device comprising a line of posts, a grooved pulley at each end of the line, an endless cable extending over the pulleys, a mail-box secured by a hanger or 100 hangers to the cable, a crank operatively connected with one of the pulleys, brackets fixed on the posts intermediate the ends of the line, spring-closed grooved sheaves mounted on the brackets for guiding and 105 supporting the cable, and means to prevent swinging of the mail-box while its hanger passes between the sheaves, substantially as and for the purpose set forth.

3. A mail-carrying device comprising a 110 line of posts, a grooved pulley at each end of the line, an endless cable extending over the pulleys, a mail-box secured by a hanger or hangers to the cable; and a crank operatively connected with one of the pulleys, the 115 terminal post at one or both ends of the line having a horizontally-projecting arm or frame supporting the pulley beyond the post, so as to deliver the box out over a wagon or into a house, as the case may be.

4. A mail-carrying device comprising a line of posts, a grooved pulley at each end of the line, an endless cable extending over the pulleys, a mail-box secured by a hanger or 120 hangers to the cable; a crank operatively connected with one of the pulleys, brackets fixed on the posts intermediate the ends of the line, spring-closed grooved sheaves mounted on the brackets for guiding and 125 supporting the cable, and means for guiding the 130

idle strand of the cable, substantially as set forth.

5. A mail-carrying device comprising a line of posts, a grooved pulley at each end of the line, an endless cable extending over the pulleys, a mail-box secured by a hanger or hangers to the cable, a crank operatively connected with one of the pulleys, a signal-bell and hammer adapted to strike on the 10 bell at one end of the line, a hand-operated

lever at the other end of the line, and a guided wire extending from the lever and operatively connected with the hammer, for the purpose set forth.

In testimony whereof I affix my signature 15 in presence of two witnesses.

HANS PEARSON.
